FIG. 1

FIG 2

INVENTOR
REGINALD LUMSDEN
By *Gettmanhaugh & Co*
Atlys.

UNITED STATES PATENT OFFICE.

REGINALD LUMSDEN, OF HAMILTON, ONTARIO, CANADA.

WRENCH.

1,399,633.

Specification of Letters Patent.

Patented Dec. 6, 1921.

Application filed January 24, 1921. Serial No. 439,557.

To all whom it may concern:

Be it known that I, REGINALD LUMSDEN, a subject of the King of Great Britain, residing in the city of Hamilton, county of 5 Wentworth, Province of Ontario, Canada, have invented certain new and useful Improvements in Wrenches, of which the following is the specification.

My invention relates to improvements in 10 wrenches and the object of the invention is to provide for very rapid and convenient adjustment of the wrench to suit widely varying sizes of work.

My invention consists of the ordinary 15 monkey wrench in which the movable jaw is operated by a worm carried thereby and which engages a suitable rack upon the shank of the wrench, the worm being mounted in a bracket which is pivotally 20 mounted in the movable jaw whereby the worm may be swung laterally out of operative engagement with the rack of the shank to permit free movement of said movable jaw, all as hereinafter more particularly 25 described and illustrated in the accompanying drawings in which—

Figure 1 is a side view of a wrench constructed according to my invention, a portion 30 of the movable jaw being broken away to show the construction, the section being through the center of the jaw.

Fig. 2 is a transverse section on the line 2, 2 of Fig. 1 looking in the direction of the arrows, the worm being shown swung 35 to one side out of operative engagement with the shank.

Like characters of reference indicate corresponding parts in the different views.

1 is the shank or handle portion of the 40 wrench which carries the fixed jaw 2 at one end thereof.

3 is the movable jaw which is provided with the passageway 4 through which the shank 1 extends.

45 The inner face of the shank 1 is provided with the rack 5.

The body of the jaw 3 is provided with a rectangular opening 6 for a purpose as will presently appear.

50 7 is a bracket which is mounted in the movable jaw 3 and is capable of being swung laterally in the opening 6 about the axis $\alpha-\alpha$.

The upper end of the bracket is jour-

naled in the movable jaw by means of the 55 pin 8 engaging a suitable bearing orifice in the jaw.

The lower end of the bracket is journaled in the jaw by means of the pin 9 which extends freely through the orifice 10 60 in the jaw and has its inner end threaded at 11 to engage a correspondingly threaded orifice in the bracket 7.

12 is a worm which is rotatably mounted in the bracket 7. The upper end of the 65 worm carries a journal pin 13 which engages a bearing orifice in the bracket 7. The lower end of the worm is journaled in the bracket by means of the pin 14 which extends freely through the orifice 15 in the 70 bracket and has its inner end threaded at 16 to engage a correspondingly threaded orifice in the worm.

The movable jaw is provided with a passageway 17. Into this passageway is 75 inserted the locking ball 18 which projects partially through the lower end and is adapted to engage the dimple 19 on the top face of the bracket 7 when the bracket is in the position shown in Fig. 1. The 80 lower end of the passageway 17 is slightly restricted to prevent the ball 18 from passing entirely through.

The coil spring 19 is located in the passageway 17 above the ball 18 and is held in 85 position by the screw cap 20 which is threaded into the upper end of the passageway 17.

The construction and operation of my device is as follows:—

The fixed jaw 1 and the shank with the rack 5 are of standard construction, commonly used on wrenches of this type.

Considering the parts in the position illustrated in Fig. 1, it will be evident that the 95 jaw 3 is locked and can only be moved along the shank by rotating the worm. Also in this position the ball 18 is engaging the dimple 19 in the bracket 7 so that the worm is held in the correct operative engagement 100 with the rack 5.

In this position the jaw 3 may be adjusted by means of the worm to tightly grip the work.

When it is desired to use the wrench on 105 work requiring a different jaw opening, instead of having to move the jaw 3 all the way by means of the worm, which involves

a considerable waste of time, the bracket 7 may be swung to one side about the axis $x-x$ (see Fig. 1).

This position is shown in Fig. 2 and it will be seen that the worm is now entirely out of engagement with the rack 5 on the shank so that the jaw 3 may be freely moved to any desired position. In order to tighten the jaws upon the work, the bracket is swung back into the position in Fig. 1 and further adjustment done by means of the worm.

The pins 9 and 14 with their threaded inner ends permit of convenient assembling of the wrench.

Ordinarily on wrenches of this type, the movable jaw can only be moved by means of the worm and it is with a view of enabling more rapid and convenient adjustment that my improvements have been devised. This improvement will be particularly valuable in the case of large wrenches in which the movable jaw has a very considerable length of travel along the shank.

I am aware that various methods of accomplishing this end have been tried but without success since they have interfered with the reliability of the grip of the jaws and have rendered the movable jaw liable to slip in certain positions of the worm.

One method used consisted in providing a longitudinal groove in the worm so that when this groove registered with the rack the movable jaw was free for rapid adjustment. This was subject to the above disadvantage however.

While I have illustrated one specific form in which my invention may be made, it is to be understood that various alterations could be made in the exact details of con-

struction without departing from the spirit 40 of my invention. For instance other methods of mounting the bracket 7 and worm 12 might be used in place of the pins 9 and 14 as illustrated. Also the opening 6 need not be rectangular.

From the foregoing it will be seen that I have devised valuable improvements in wrenches which will make their use more convenient and also result in a considerable saving of time in making adjustments.

What I claim as my invention is:

A wrench comprising a shank portion, a fixed jaw carried integrally thereby, a movable jaw slidably mounted upon the shank, a longitudinally disposed rack on the shank, the movable jaw having a rectangular transverse opening therein, a bracket having a vertical portion and an upper and lower horizontal arm extending from its upper and lower end respectively, the bracket being pivotally mounted within the rectangular opening in the movable jaw and being capable of being swung laterally therein about its pivot points, the lower pivotal connection of the bracket comprising a screw member whereby the bracket is detachably mounted in the movable jaw, a worm rotatably mounted in the bracket and co-acting with the rack, the top face of the upper horizontal arm of the bracket provided with a dimple, and a spring held ball carried in an orifice in the movable jaw and adapted to engage the dimple for locating the worm and rack in their engaged positions.

REGINALD LUMSDEN.
